Inventor:

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,820, dated February 26, 1884.

Application filed January 23, 1884. Term of patent 3½ years.

To all whom it may concern.

Be it known that I, CATHERINE O'HARA, of the city, county, and State of New York, have invented and produced a new and original Design for a Pattern of a Lady's Costume, (numbered 9,068;) and I do hereby declare that the engraved prints accompanying this specification convey to any one accustomed to using paper patterns a clear understanding of how a garment made up by the pattern will appear.

The design shows a walking-skirt and an overdress. The overdress shows a closely-fitted polonaise-front falling in a deep point at the right side, and exhibiting draping-plaits in its left-side edge, and exposing a V-shaped

vest between the edges of a lengthwise opening in the upper part of its center; a deep, polonaise-back, exhibiting deep loopings in its front edges and other loopings at the center; coat-sleeves, and a standing-collar.

What I claim as my invention, and desire to secure by Letters Patent, is—

The design for a lady's costume, as shown in the engraved prints accompanying this specification.

CATHERINE O'HARA.
